(57) **CLAIM**

The ornamental design for a dart shaft, as shown and described.

DESCRIPTION

FIG. 1 is a left side elevational view of a dart shaft according to a first embodiment of the invention.

FIG. 2 is a front elevational view thereof.

FIG. 3 is a top plan view thereof.

FIG. 4 is a right side elevational view thereof.

FIG. 5 is a bottom plan view thereof.

FIG. 6 is a rear elevational view thereof.

FIG. 7 is an exploded front perspective view thereof.

FIG. 8 is a front perspective view thereof.

FIG. 9 is a rear perspective view thereof.

FIG. 10 is a left side elevational view of a dart shaft according to a second embodiment of the invention.

FIG. 11 is a front elevational view thereof.

FIG. 12 is a top plan view thereof.

FIG. 13 is a right side elevational view thereof.

FIG. 14 is a bottom plan view thereof.

FIG. 15 is a rear elevational view thereof.

FIG. 16 is an exploded front perspective view thereof.

FIG. 17 is a front perspective view thereof.

FIG. 18 is a rear perspective view thereof.

FIG. 19 is a left side elevational view of a dart shaft according to a third embodiment of the invention.

FIG. 20 is a front elevational view thereof.

FIG. 21 is a top plan view thereof.

FIG. 22 is a right side elevational view thereof.

FIG. 23 is a bottom plan view thereof.

FIG. 24 is a rear elevational view thereof.

FIG. 25 is an exploded front perspective view thereof.

FIG. 26 is a front perspective view thereof; and,

FIG. 27 is a rear perspective view thereof.

The broken lines in various figures form no part of the claimed design.
